UNITED STATES PATENT OFFICE

129,827

DESIGN FOR A PLATTER OR OTHER
ARTICLE OF HOLLOW WARE

Jean G. Theobald, Meriden, Conn., assignor to
International Silver Company, Meriden, Conn.,
a corporation of New Jersey

Application August 12, 1941, Serial No. 102,799

Term of patent 14 years

To all whom it may concern:

Be it known that I, Jean G. Theobald, a citizen of the United States, residing at Meriden, county of New Haven, State of Connecticut, have invented a new, original, and ornamental Design for a Platter or Other Article of Hollow Ware, of which the following is a specification, reference being had to the accompanying drawing, forming a part thereof.

Fig. 1 is a top plan view of a platter showing my design, it being understood that the ornamentation is continued around the entire circumference of the platter;

Fig. 2 is a fragmentary view of the ornamenta-

tion only, on an enlarged scale, for the purpose of bringing out the details of the design; and

Figs. 3 and 4 are sectional views along the lines A—A and B—B respectively of Fig. 2.

The design is here shown as applied to a platter, but it is also intended for use on sets comprising various articles of hollow ware for table use.

I claim:

The ornamental design for a platter or other article of hollow ware, substantially as shown and described.

JEAN G. THEOBALD.
